UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER LOOM.

Application filed August 19, 1918. Serial No. 250,412.

To all whom it may concern:

Be it known that I, JONAS NORTHRUP, a citizen of the United States, residing at Hopedale, in the county of Worcester and State of Massachusetts, have invented certain new and useful Improvements in Feeler Looms; and I do hereby declare the following to be a full, clear, and exact description of the invention, such as will enable others skilled in the art to which it appertains to make and use the same.

The present invention relates to an improvement in looms, and more particularly the invention relates to an improvement in center fork filling detector mechanism for looms.

The invention is particularly adapted for application to feeler looms which are a type of automatic weft replenishing loom in which the higher grades of fabrics are woven. Such looms are provided with a filling feeler mechanism which measures the amount of filling in the active shuttle, and when the filling has been exhausted to a critical or predetermined extent, causes the weft replenishing mechanism to insert a fresh supply of filling in the shuttle. The employment of the filling feeler mechanism to control the operation of the weft replenishing mechanism is for the purpose of avoiding the presence of short wefts or mispicks in the woven fabric. In case the filling should become completely exhausted, owing to a defective filling feeler action, or in case the filling should break, the loom is stopped by the action of a filling detector mechanism with which feeler looms are usually provided. If the filling feeler mechanism is located at either end of the loom, that is to say, beside either selvage, broken wefts are liable to be woven into the cloth and be undetected by these filling detector mechanisms. Accordingly feeler looms are often provided with a filling detector mechanism in which the filling fork is mounted on the middle of the lay. These forks perform their filling detecting operations on every beat-up of the lay and cause loom stoppage in case the filling should be absent from the middle of the shed. Such filling detector mechanisms are known in the art as center fork filling detector mechanisms.

One object of the present invention is to produce a center fork filling detector mechanism of such construction that when the

filling fork performs its filling detecting operation, it is entirely disconnected from its actuating means and descends upon the filling with only the force of the descending fork tines. The filling detecting operation is therefore very sensitive and the filling or weft is not stretched or otherwise injured by the action of the fork tines.

A further object of the invention is to produce a center fork filling detector mechanism which will be rendered inoperative or functionless on the first beat-up of the lay after the weft replenishing operation. The reason for rendering the filling detector mechanism inoperative on this beat-up is, because the end of the new filling is attached to the hopper stud and the filling pays out from the bobbin over the middle of the eye or delivery end of the shuttle, and consequently relatively near the reed. This laying of the filling relatively near the reed on the first pick of the shuttle after the replenishing operation results in the center filling fork often failing to detect the presence of the filling, because of the fact that the filling is beyond the end of the fork tines. The end of the fork tines is necessarily separated from the reed a considerable distance because of the construction of the lay and the reed at that point. By rendering the filling detector mechanism inoperative or functionless on this beat-up of the lay, the possibility of the filling fork missing the newly inserted filling, and consequently stopping the loom, is obviated.

Still further object of the invention is to produce a center fork filling detector mechanism of such construction that it is rendered inoperative or functionless on the first beat-up of the lay when the loom is re-started after the stoppage thereof. This rendering of the filling detector mechanism inoperative or functionless at this time is made necessary by the fact that it is universally the custom among operators when the loom is stopped for any reason, to "turn the loom over" by hand, in order to remedy the defect causing the stoppage. If the loom is stopped because of warp breakage, a filling will generally be present in the shed as the lay advances on the beat-up on which the loom is usually stopped. Consequently, when the operator turns the loom over the filling and the center fork

will frequently be disengaged from each other so that the fork will fall into its recess, and therefore when the loom is started up again, it will immediately be stopped because of the fact that the fork is in the position it assumes when filling is absent.

Another object of the invention is to produce a center fork filling detector mechanism in which the time of the rising and falling movements of the fork are capable of relative adjustment. In turning a loom over by hand the flight of the shuttle occurs at a higher speed relative to the movement of the lay than when the loom is being operated by power; that is to say, the flight will be completed before the lay has travelled its normal distance away from the fell. For this reason, the shuttle will sometimes strike the fork, bending the tines and causing injury to the fabric when the loom is turned over by hand. Therefore it is desirable that the time of lifting the fork shall be so adjusted as to occur on the movement of the lay to the rear as soon as the tines will clear the fell. The time at which the fork drops, however, should not be affected by the adjustment of the time at which it is lifted.

These objects of the invention and such further objects as shall hereinafter appear are accomplished by the improved feeler loom having the center fork filling detector mechanism hereinafter described and particularly pointed out in the appended claims.

The preferred form in which it is contemplated embodying the invention is illustrated in the accompanying drawings, in which Figure 1 is a plan of the filling feeling end of a loom to which the various mechanisms of the present invention are applied, together with a portion of the lay showing the application of the improved center filling fork thereto; Fig. 2 is a sectional elevation of the left-hand portion of the parts shown in Fig. 1; Fig. 3 is a front elevation of the center filling fork and of a part of the mechanism for actuating it; Fig. 4 is a section through the lay showing the improved center fork in end elevation, looking from the right in Fig. 3; Fig. 5 is a section taken along the line 5-5 of Fig. 3; Figs. 6 to 9 inclusive are diagrammatic views showing the action of the fork actuating member on the center fork when filling is present and absent; Fig. 10 is a perspective view of the center fork actuating member; and Fig. 11 (Sheet 1), is a diagrammatic view showing the interrelation of the various elements of the loom embodying the present invention.

The feeler loom to which the features of the present invention are applied may be of any usual or preferred form. In the type of feeler loom illustrated in the drawings,

the filling feeler mechanism indicated generally at F. F. M. is mounted on a bracket attached to one end of the breast beam 12, and the weft replenishing mechanism, indicated diagrammatically at W. R. M. in Fig. 11, is mounted on the other end of the breast beam. The two mechanisms are operatively connected by a hollow rock or change shaft 13 which is journaled in brackets on the front of the breast beam 12 and extends longitudinally thereof. The function of the filling feeler mechanism is to determine the state of exhaustion of the filling in the active shuttle. When the filling has been exhausted to a predetermined extent, the feeler member 14 swings contra-clockwise, viewing Fig. 1, under the propulsion of a spring 15 which is interposed between a change lever 16 (pivoted at 17 on an arm 18 secured to the change shaft 13) and a latch lever 19 pivoted at 20 on the change lever 16. The feeler member 14 and the latch lever 19 are connected by a link 21. The contra-clockwise swinging of the feeler member 14 and the latch lever 19, viewing Fig. 1, moves the notched end 23 of the latch lever into the path of movement of the weft hammer 24, and thereupon, owing to the forward movement of the change lever 16, the arm 18 and the change shaft 13 are oscillated to initiate the weft replenishing operation.

As is usual with feeler looms, the loom is stopped on the detection of filling absence. The loom stopping means comprises the shipper 25 which, when the loom is operating, is thrown forwardly against one end of a shipper or knock-off lever 26 pivoted at 27 on a bracket extending outwardly from the breast beam. When filling absence is detected by the center fork filling detector mechanism constituting the subject-matter of the present invention, the shipper or knock-off lever 26 is caused to turn clockwise, viewing Fig. 1, thereby knocking off the shipper 25 and stopping the loom. The parts above described, together with the lay and its parts, constitute the weaving devices and all these parts are of usual construction and well-known to those skilled in the art.

The center fork filling detector mechanism of the present invention comprises a filling fork consisting of a series of fork tines 30 which are separated from each other substantially the distance of three or four warp threads. These fork tines are adapted to be received in a recess 31 in the race-way of the lay 32. As is usual with center filling forks, the lower group 33 (Fig. 5) of warp threads constitutes the fork grid with which the fork tines 30 cooperate. When the shuttle, in its flight through the shed 34 leaves a filling behind it, the filling, indicated at 35 in Fig. 5, lies on the bottom group of warp threads.

Thereupon, the fork tines 30, which are raised previous to the passage of the shuttle past the fork tines, descend upon the filling 35, as shown in Fig. 5, thereby preventing 5 the loom stopping means from being set in operation. But when the shuttle fails to lay a thread in the shed, the fork tines 30 descend into the recess 31 and the loom stopping means are caused to be actuated and the 10 loom to be stopped.

The fork tines 30 are secured at their forward ends in a hub 36 integral with a shaft 37 pivotally supported at each end on the pointed ends of two setscrews 38 adjustably received in ears 39 of a bracket 40 secured to the front of the lay and half way between the selvages. The fork tines 30 are raised just previous to the passage of the shuttle through the shed by the action of a 20 fork actuating cam or cam member 42 which is pivoted at 43 on a downward extension of the bracket 40. The fork actuating cam member is T-shaped and the cross-piece or cam part thereof is provided with an active 25 portion or rise 45 which is adapted to cooperate with a cam finger 46 depending downwardly from the hub 36 and interposed between the cam member and the lay.

The construction of the above-described 30 parts is such that when the cam member 42 swings to the left (viewing Fig. 3), the rise 45 of the cam member engages the cam finger 46 so that the shaft 37 is thereby oscillated to raise the fork tines 30 sufficiently high to 35 permit the shuttle to pass through the shed without touching them. Depending from the forward side of the hub 36 so as to engage the cam member 42 on the side opposite to that on which the finger 46 engages it, 40 is a second cam finger 53 which is adapted to be engaged by the active part 62 of the fork actuating cam 42. When the cam member 42 is moved to the right (viewing Fig. 3), the active part 62 of the cam engages the cam finger 53 and thereby causes 45 the fork tines to descend into filling detecting position toward the filling. It will be observed that both the cam fingers 46 and 53 are only in contacting engagement with the 50 cam surfaces of the fork actuating cam 42, and that, consequently, when the cam member 42 swings to the right and the active part 62 of the cam member has engaged the cam finger 53 to depress the fork tines, further 55 movement of the cam member 42 to the right has no actuating influence on the fork, which 60 completes its filling detecting operation solely under the influence of gravity and the momentum imparted to it by the cam member. There is thus secured a very light and delicate center fork filling detecting action which can have no detrimental effect on the filling. It is believed that this is the first 65 instance in which a center filling fork is entirely disconnected from its actuating

mechanism to perform the filling detecting operation by the weight and momentum of the fork only.

It will be observed by reference to Figs. 5 and 10 and to Figs. 6 to 9 inclusive that the active part of the cam member 42 is provided with a cutaway portion 48 which permits a hook 49 to be formed on the left-hand end of the cam member. When filling is present, the fork actuating cam 42 swings to the limit 70 of its rightward movement (viewing Fig. 3) against a stop 44; but when filling is absent, the cam finger 46 of the fork is received in the cutaway portion 48, and thereupon the hook 49 engages the finger 46, which arrests further movement of the cam member; thereupon the loom stopping means are thrown into operation to stop the loom.

The fork actuating cam 42 is moved in one direction to raise the fork tines and is moved in the opposite direction to permit the fork tines to descend. The means for actuating the cam member 42 comprise a lever 50 pivoted at 51 on a bracket 52 secured to the front of the lay. The upper arm 54 of the lever 50 is connected with the cam member 42 by means of a link 55 provided with an adjustment block 56 by which the interrelation between the lever 50 and the cam member 42 may be adjusted. The lever 50 is rocked to move the fork by a belt 58 which passes around a grooved pulley 59 integral with the lever. One end of the belt is secured to a pin 60 adjustably mounted on the loom frame and the other end is connected by a spring 61 with a stud formed on the bracket 52. When the lay starts to the rear, the belt 58 is pulled around the pulley 59 and the spring 61 is distended to compensate for the increased distance between the lay and the pin 60 to which the belt is fastened. This turns the pulley thereby swinging the arm 54 to the left, viewing Fig. 3, and raising the fork.

The fork should not be raised, however, until the lay has travelled a sufficient distance to the rear to allow the tines to clear the fell. In order that the fork may be raised when it will clear the fell and that the raising of the fork may be adjusted to occur at the earliest possible moment after such time, the movement of the pulley 59 under the influence of the belt 58 is delayed. The means for restraining the movement of the pulley comprises a cam plate 63 adjustably secured to the loom frame by a bolt 64 and an arm 65 formed integral with the lever 50 and pulley 59. When the lay is on the front center, as shown in Figs. 2 and 3, the arm 65 lies above the cam plate 63 and as the lay moves to the rear the lever 50 is restrained from movement until the arm has passed beyond the end of the cam plate. This construction causes the belt 58 to slip over the pulley 59 until the control of the cam plate 115 120 125 130

ceases, at which time the pulley will be rocked by the belt and the fork raised. The speed with which the fork is actuated may be varied by increasing or decreasing the diameter of the pulley 59. It is apparent that the time of raising the fork may be varied by adjusting the position of the cam plate 63 so that it shall be raised as soon as it will clear the fell and thus avoid being struck by the shuttle whether the loom be actuated by hand or power. After the lever 50 has been turned until the arm 54 engages a stop lug 66, the belt again slips in the groove of the pulley until the lay reaches the rear center. A guide block 152 keeps the belt from running out of the groove on the pulley 59. The belt 58 will slip over the pulley 59 at any time that the movement of the fork or the actuating cam 42 is resisted. This provides a frictional actuation of the parts as distinguished from a positive movement which can not be stopped without injury to the mechanism.

The fork is lowered by the action of the spring 61 in taking up the slack in the belt as soon as the lay starts to the front. After the pulley has been turned sufficiently to cause the arm 54 to engage a stop lug 154, the belt slips over the pulley as before but in the opposite direction. It is thus seen that the cam member 42 is actuated in alternate directions first to raise the fork tines, and then to depress the fork tines part way and thereafter allow them to drop under the action of gravity to detect the absence or presence of the filling.

The mode of operation of the center filling fork and its cam actuating member 42 is illustrated diagrammatically in Figs. 6 to 9 inclusive. Fig. 6 represents the relation between the fork actuating cam and the fork fingers 46 and 53 when the parts are in the positions shown in Figs. 1 and 3, which represent the lay on its forward center, that is to say, at the limit of its forward movement, with the reed beating the filling against the fell. When the fork actuating cam has been moved to lift the fork tines, on the backward beat of the lay, the relation between the fork actuating cam and the fork fingers 46 and 53 is as shown in Fig. 9. The lay now beats up again and the fork is kept raised until the active portion 62 of the cam engages the cam finger 53, and thereupon as the active portion 62 passes the finger 53, the fork tines are depressed toward the filling, but before they have reached the filling the active part 62 passes beyond the finger 53 and so the fork tines descend upon the filling under the influence of their own momentum, the fork being at this point, as illustrated in Fig. 8, not actuated in either direction by the fork actuating cam. Just previous to the arrival of the barb of the hook 49 opposite the fork finger 46, the fork tines have descended to the level of the filling. If now the filling is present, the hook 49 will pass inoperatively by the fork finger 46, as shown in Fig. 6. But if the filling is absent, the fork tines will descend into the recess 31 and the fork finger 46 will move into the path of movement of the hook 49 (as shown in Fig. 7) and stop the further movement of the fork actuating cam 42. This will cause the arm 54 of the lever 50 to stop in a substantially vertical position, viewing Fig. 3, midway between the stop lugs 66 and 154. The swinging movement of the lever being arrested, further movement of the lay causes the belt 58 to slip over the pulley 59. This catching of the fork finger 46 by the hook 49 on the fork actuating member 42 causes the loom stopping means to be actuated on the same beat-up of the lay.

The mechanism by which the center filling fork causes an actuation of the stopping means comprises a knock-off lever actuator 67 which is slidably received in a slot in a bracket 68 secured to the breast beam. At its forward end the knock-off lever actuator is provided with a slot 69 which loosely engages a pin 70 projecting laterally from the upper end of an arm 71 which is secured to a stop shaft 72 journaled within the hollow change shaft 13. This arm 71 and stop shaft 72 do not perform in connection with the present invention any other than their usual function, and are only appendages of the feeler loom to which the various mechanisms of the present invention are applied. The slot 69 in the forward end of the knock-off lever actuator is provided so that it may move rearwards relatively to the arm 71. When the knock-off lever actuator moves forward, the arm 71 is moved outwardly to oscillate the shaft 72 which lets back and stops the take-up devices. In order that the knock-off lever actuator may cooperate with the knock-off lever to actuate the shipper, the knock-off lever actuator is provided with a lug 74 which is normally positioned immediately behind the end 75 of the knock-off lever so that when the knock-off lever actuator is moved forward, the lug 74 is pushed against the end 75 of the knock-off lever and the latter is actuated to knock off the shipper to stop the loom. Depending from the rear end of the knock-off lever actuator is a finger 77 which is adapted to be struck by a bunter 78 extending forwardly from the front upper end of the lever 50 when the fork actuating cam is held fast by the cam finger 46 on filling absence. Thereupon, the forward movement of the lay brings the bunter 78 into engagement with the lower end of the finger 77, and the knock-off lever actuator is moved forward to stop the loom. The knock-off lever

actuator in conjunction with the knock-off lever and the shipper constitutes the loom stopping devices.

The mechanism by which the center fork filling detector mechanism is rendered inoperative or functionless on the first beat-up of the lay after the replenishing operation comprises a catch 80 loosely mounted on a pivot pin 81 projecting laterally from the change lever 16. This catch 80 is normally held in the position shown in Fig. 2 by means of a downwardly projecting finger 82 which is adapted to press against the forward end 83 of the bracket 68. On the under side of its forward end, the catch 80 is provided with a hook 85 which is adapted to cooperate with a shoulder 86 formed on the upper side of the forward end of the knock-off lever actuator. When the filling 20 feeler mechanism indicates critical or predetermined exhaustion of filling and the change lever is caused to be moved forward, as before described, the hook 85 on the catch 80 drops down in front of the shoulder 86 on the knock-off lever actuator. The weft replenishing operation takes place on the beat-up of the lay succeeding the indication of critical exhaustion of filling, and during this time the change lever is held in its outward position with the hook 85 in front of the shoulder 86. As the lay beats back after the replenishing operation, the change lever 16 moves rearwardly and the hook 85 is thereby brought into engagement 30 with the shoulder 86, and as the change lever continues its rearward movement, the knock-off lever actuator is moved rearwardly therewith, moving a shoulder 88 formed on the rear under side of the knock-off lever actuator into engagement with a boss 89 projecting upwardly from the bracket 68, thereby causing the rear end of the knock-off lever actuator to be lifted into the position shown in the dot and dash lines in Fig. 2. The return of the change lever to its normal position returns the catch to its normal position. The lower end of the finger 77 is now above the path of motion of the bunter 78 on the lever 50, so that in case the fork tines do not engage the filling on the first pick of the shuttle away from the replenishing mechanism, the loom will not be stopped. The rearward movements of the change lever and the knock-off 40 lever actuator are such that the rear end of the knock-off lever actuator is lifted into its inoperative position before the fork tines descend into filling engaging position. It is to be borne in mind that the finger 77 on the rear end of the knock-off lever actuator assumes the position shown in the dot and dash lines in Fig. 2 before the lay beats forward. As the lay is completing its forward movement, a plate 90 projecting upwardly and laterally from the upper end of the lever 50 comes into engagement with the finger 77 to return the knock-off lever actuator to its normal position. The position of the plate 90 is such that its engagement with the finger 77 does not cause the lug 74 to move into engagement with the end 75 of the knock-off lever 26, and so, the loom is not stopped on this beat-up of the lay, which is the beat-up following replenishment.

The mechanism for rendering the center fork filling detector mechanism inoperative or functionless on the first beat-up of the lay when the loom has been restarted after stoppage, comprises a lever 93 pivoted on a pin 94 projecting laterally from a bracket 95 secured to the front of the bracket on which the knock-off or shipper lever is pivoted. This lever 93 carries on its upper end a cross-piece 96 which extends longitudinally of the loom, one end of the cross-piece being bent rearwardly at 97 to take against the shipper 25 and the other end 98 of the cross-piece ending in front of a lug 99 depending from the forward end of the knock-off lever actuator. A torsion spring 101 presses the lever 93 rearwardly so that the end 97 of the cross-piece 96 is pressed against the shipper 25 when the loom is in operation. When the loom is stopped for any reason the shipper is moved rearwardly, and thereupon the spring 101 causes the lever 93 and its cross-piece 96 to move rearwardly, the end 97 of the cross-piece following the shipper 25, and the end 98 of the cross-piece moving into engagement with the lug 99 to force the shoulder 88 up over the boss 89, thereby causing the knock-off lever actuator to assume the position shown in dot and dash lines in Fig. 2. The knock-off lever actuator being in this position on the first beat-up of the lay on the resumption of the loom operation, the plate 90 will come into contact with the lower end of the finger 77 of the knock-off lever actuator and will restore the latter to its normal position. As a result of this mode of operation, loom stoppage will be prevented on this beat-up of the lay, as before described, even though the operator had previously "turned the loom over" and thereby moved the filling and the fork tines out of engagement with each other.

Throughout the descriptive portion of the foregoing specification the center fork filling detector mechanism has been described as being rendered inoperative or functionless on the first beat-up of the lay following the replenishing operation, and on the first beat-up of the lay on the resumption of the loom operation following the stoppage thereof. It will be understood from the description of the construction of the various parts of the center fork filling detector mechanism that the center fork itself continues in opera-

tion but that it is prevented from causing loom stoppage even though filling should be absent on these two described occurrences. It is in this sense that the word "inoperative" is used throughout the claims.

The objects of the present invention have been set forth and a specific form of center fork filling detector mechanism capable of accomplishing these objects has been described. It will be understood, however, that the invention is not limited to the specific forms of mechanism shown and described for accomplishing these objects, but that this mechanism may be constructed in other forms and yet be within the scope of the invention as set forth in the following claims.

Having thus described the invention, what is claimed is:

20. 1. A weft replenishing loom having, in combination, loom controlling devices, a filling feeler mechanism, a filling detector mechanism, and connections between the two mechanisms having provision whereby the loom controlling devices are rendered inoperative on the first pick of the shuttle after replenishment.
25. 2. A loom having, in combination, weft replenishing mechanism, filling feeler mechanism therefor, loom stopping devices, a filling detector mechanism and connections between the loom stopping devices and the filling detector mechanism, the loom stopping devices having provision whereby they are rendered inoperative during the first beat-up of the lay after replenishment.
30. 3. A loom having, in combination, weft replenishing mechanism, filling feeler mechanism therefor, loom controlling devices, a center fork filling detector mechanism and connections between the filling feeler mechanism and the filling detector mechanism including a device for preventing the operation of the loom controlling devices during the first beat-up of the lay after replenishment.
35. 4. A loom having in combination, loom controlling devices including a change lever and a filling detector mechanism including a lever mounted on the lay having a bunter, loom stopping devices including a knock-off lever actuator adapted to be engaged by the bunter on the detection of filling absence, and connections between the change lever and the knock-off lever actuator whereby the latter is moved into inoperative position out of the range of movement of the bunter on an actuation of the loom controlling devices.
40. 5. A loom having, in combination, a filling detector mechanism including a lever mounted on the lay having a bunter, stopping devices including a knock-off lever actuator adapted for engagement by the bunter to actuate the shipper to stop the loom on the detection of filling absence, loom controlling devices, and connections between the loom controlling devices and the knock-off lever actuator constructed and arranged to move the latter out of the path of movement of the bunter on the first beat-up of the lay after an actuation of the loom controlling devices.
45. 6. A loom having, in combination, a weft replenishing mechanism, a center fork filling detector mechanism, loom stopping devices adapted to be set in operation by the filling detector mechanism to stop the loom on the detection of filling absence, and connections between the weft replenishing mechanism, the loom stopping devices and the filling detector mechanism having provision for preventing the filling detector mechanism from effecting an operation of the loom stopping devices on the first beat-up of the lay after the weft replenishing operation.
50. 7. A loom having, in combination, a filling feeler mechanism, a weft replenishing mechanism, a filling detector mechanism, connections between the three mechanisms, stopping devices adapted to be actuated to stop the loom on the detection of filling absence, said connections between the mechanisms having provision for preventing the operation of the filling detector mechanism upon the stopping devices on the first beat-up of the lay following the replenishing operation.
55. 8. A loom having, in combination, a filling feeler mechanism, a weft replenishing mechanism, a filling detector mechanism, operative connections between the three mechanisms, loom stopping devices including a shipper, and means connected with the shipper and with the connections between the three mechanisms having provision for rendering the stopping devices ineffective on the first beat-up of the lay following a resumption of loom operation after the stoppage thereof.
60. 9. A loom having, in combination, a weft replenishing mechanism, stopping devices, a center fork filling detector mechanism adapted to cause the stopping devices to be set in operation to stop the loom on the detection of filling absence, and means for preventing the filling detector mechanism from causing the stopping devices to be set in operation on the first beat-up of the lay following the weft replenishing operation.
65. 10. A loom having, in combination, a weft replenishing mechanism, a filling feeler mechanism connected therewith, loom stopping devices, a filling detector mechanism for causing the loom stopping devices to be set in operation on the detection of filling absence, and connections between the filling feeler mechanism and the loom stopping devices having provision for preventing the filling detector mechanism from causing the loom stopping devices to be set in operation on the first beat-up of the lay following the weft replenishing operation.

11. A loom having, in combination, weft replenishing mechanism, filling feeler mechanism, connections between the weft replenishing mechanism and the filling feeler mechanism for setting the latter in motion on critical filling exhaustion, a filling detector, loom stopping devices, connections between the filling detector and the loom stopping devices operating, on absence of filling, to stop the loom, and connections between the filling feeler mechanism and the loom stopping devices operating to prevent actuation of the stopping devices by the detector on the first beat up of the lay following weft replenishment.
12. A loom having, in combination, weft replenishing mechanism, filling feeler mechanism, connections between the filling feeler mechanism and the weft replenishing mechanism operating to cause weft replenishment on critical filling exhaustion, loom stopping devices, a filling detector, connections between the loom stopping devices and filling detector for stopping the loom on the absence of filling, and connections between the filling feeler mechanism and the filling detector operating to prevent the filling detector from initiating loom stoppage on the first beat up of the lay after replenishment.

JONAS NORTHRUP.
